UNITED STATES PATENT OFFICE.

WILLIAM C. WHITCOMB, OF CHICAGO, ILLINOIS, ASSIGNOR TO GEORGE D. WHITCOMB COMPANY, A CORPORATION OF ILLINOIS.

KNITTING-MACHINE.

No. 838,065.

Specification of Letters Patent.

Patented Dec. 11, 1906.

Application filed March 31, 1905. Serial No. 253,071.

To all whom it may concern:

Be it known that I, WILLIAM C. WHITCOMB, a citizen of the United States, and a resident of Chicago, county of Cook, and State of Illinois, have invented certain new and useful Improvements in Knitting-Machines, of which the following is a specification and which are illustrated in the accompanying drawings, forming a part thereof.

10 The invention relates to knitting-machines, and particularly to those which produce a fabric comprising a succession of articles adapted to be separated.

One of the objects of the invention is to 15 provide improved means for the formation of a lock-stitch, and, as the machine is organized, particularly for forming a lock-stitch as the connecting-web between successive articles, so that when separated each 20 may have a selvage edge.

A further object is to provide improved means for forming a half cardigan-stitch and for changing from this to other forms of stitches.

25 Further minor objects will be developed in the description of the machine.

The interlocked stitches are formed by what is known in the art as "racking." It consists in alternately shifting one of the needle-plates back and forth longitudinally with reference to the other between several succeeding forward and return strokes of the cam-carriages. In this way each of the needles of one set is advanced to receive the yarn alternately into each of two adjacent interspaces of the other set of needles. In the machine to be described this racking movement is produced during the formation of several rows of knitting in the formation of the body of each 40 garment, as well as at the point where the articles are to be separated, in order to give a more finished appearance to the fabric.

The invention consists in the construction and arrangement of parts to be hereinafter described, and which are illustrated in the accompanying drawings, in which—

Figure 1 is a side elevation of the machine. Fig. 2 is a detail end elevation of the same. Fig. 3 is a detail longitudinal vertical section 50 on the line 3 3 of Fig. 2. Fig. 4 is a detail cross-section on the line 4 4 of Fig. 3. Fig. 5 is an inclined elevation as viewed from the line 5 5 of Fig. 2. Fig. 6 is a bottom plan view of one of the cam-carriages. Fig. 7 is a

sectional view of the same on the line 7 7 of 55 Fig. 8. Fig. 8 is a detail cross-section of the machine on the line 8 8 of Fig. 5. Fig. 9 is a detail section on the line 9 9 of Fig. 8. Fig. 10 is a section taken on the line 10 10 of Fig. 2. Fig. 11 is a detail end elevation of the 60 machine as viewed from the line 11 11 of Fig. 10. Fig. 12 is a detail of Fig. 2, showing the parts in a different position. Fig. 13 is a sectional view on the line 13 13 of Fig. 10. Fig. 14 is similar to Fig. 10, but showing the parts 65 in a different position. Fig. 15 is a detail section on the line 15 15 of Fig. 14. Figs. 16 and 17 are sectional views on the lines 16 16 and 17 17, respectively, of Fig. 3. Fig. 18 is a detail section on the line 18 18 of Fig. 3. 70 Fig. 19 is a sectional view taken on the line 19 19 of Fig. 18. Fig. 20 is a detail section on the line 20 20 of Fig. 2. Fig. 21 shows a modification in the construction, and Fig. 22 shows in detail some of the parts illustrated 75 in Fig. 3.

In the drawings there is shown a straight type of knitting-machine having two co-operating banks of needles. Some of the parts not included in the invention are shown conventionally, and others which have no bearing at all upon the operation of the parts involved in the invention have been omitted entirely.

The machine is carried by a frame comprising uprights 50, 51, and 52, the floor-plate 53, lower side rails 54 55, and upper side rails 56 and 57. Cam-carriages are shown at 58 and 59 and a frame for a yarn-carrier at 60, these parts being adapted to reciprocate over the needle-plates 63 and 64. For this purpose rods 61 and 62 are joined to the cam-carriages and are united by a cross-head 65, which travels in ways 66, formed in the upper side rails 57. This cross-head is 85 driven by a mechanism which in its simplest form may consist of a swinging lever 67, pivoted to the cross-head and fulcrumed at the base of the machine. As the cross-head 65 moves in a straight line, it is important that 90 the fulcrum for the lever 67 be movable, and to this end a link 68 is pivoted to the lower end of the lever and to a floor-hanger 69, secured to the floor-plate 53. The lever 67 is actuated by means of a pitman 70, driven by 95 a crank 71 on a shaft 72, journaled in the lower side rails 54 55.

At the back of the machine a large gear is

mounted upon this shaft, which meshes with a pinion 74 upon a counter-shaft 75, which is provided with the usual belt-pulleys 76. The counter-shaft 75 is extended through to the front of the machine and provided with a hand-wheel 77, which finds convenient use in setting up the machine.

The needle-plates 63 and 64 are provided with the usual transverse slots or needle-ways 78, in which are fitted needles 79 of usual form, each having a cam-engaging lug 80 extending upwardly into the path of the cam-carriage and resting upon a needle-supporter 81, which is provided with a downwardly-projecting finger 82, riding upon a pattern-cylinder 83, having elevated and depressed portions, as 84, for raising and lowering the needle into and out of action.

Each of the cam-carriages 58 and 59 is provided with an advancing cam-plate 85, which has double-inclined cam-surfaces 86 and 87 for engaging the needle-lugs when moving in either direction. There are also provided for each carriage two retracting-cams 88 and 89, which, as their position determines the tension of the knitting, are movably attached to the cam-carriages by means of pins 90, moving in slots 91 in the floor of the carriage. Each of these retracting-cams is slotted as usual, as shown at 92, this slot receiving a wrist-pin 93 upon a crank-disk 94 at the base of an upright shaft 95, journaled in the frame of the carriage. This shaft is provided at its upper end with a worm-wheel 96, meshing with a worm 97, journaled in a bracket-arm 98, rising from the back of the carriage and running upon a square shaft 99, extending over the needle-plate for its entire length and journaled in brackets 100 101, rising from the frame of the machine.

The square shafts 99 and the pattern-cylinder 83 are intermittently driven, as may be desired to produce the required pattern in the fabric, by means of a pattern mechanism carried by the end upright 50 of the frame of the machine. The pattern-cylinder 83 is extended in either direction by shaft-sections 102 and 103, which are journaled, respectively, in the end plate 50 and in a hanger 104, depending from the inner end of the needle-plate, the cylinder being free to rotate independently of the shaft-section 103, but movable longitudinally therewith.

A pawl-arm 105, Fig. 16, carrying a spring-pawl 106, is rotatably mounted on the outer end of the shaft 102 and co-operates with a ratchet-wheel 107, fixed to such shaft. A dog 108 is pivoted to the frame of the machine and engages the teeth of the ratchet-wheel 107 to prevent its turning in the opposite direction. A cam-plate 109 is provided for swinging the pawl-arms so as to advance the pattern-cylinders 83. This cam-plate is mounted upon a hollow sleeve 111, support-

ed by a stud 112, securely fixed in the frame 65 of the machine. A spring 110 reacts between the pawl-arms 105 to insure their engagement with the face of the cam-plate 109.

The hollow sleeve 111 and its cam-plate 109 are driven from the main driving-shaft of 70 the machine. As the mechanism for transmitting the motion forms no part of the present invention, it is conventionally shown to be as follows: A shaft 113 extends along the machine from the upright 51 and projects 75 through the face of the end plate 50. This shaft is driven from the shaft 72 by means of skew-gears 114 and carries on its forward end a pinion 115, which through the medium of an idler 116 drives a gear 117, keyed to the 80 hollow shaft 111.

Each of the square shafts 99 carries on its forward end a pinion 118, which meshes with a gear-rack 119, extending across the end of 85 the machine and supported by guides projecting from the brackets 100. This gear-rack is joined by a link 120 to a bell-crank lever 121, pivoted to the frame of the machine at 122 and operatively connected by a tension-rod 123 to a swinging lever 124. 90 From the forward end of this lever a cam-engaging finger 126 projects into the path of cam-blocks 127, secured to the face of a pattern-ring 128 and adapted to swing the lever 124 and reciprocate the gear-rack 119 when 95 they come into engagement with the finger 126. A spring 125 reacts between the frame of the machine and the lever to return it to its normal position when its forward end becomes disengaged from the cam-block. 100

The pattern-ring 128 is driven in the following manner: A beveled gear 129 is formed upon the inner face of the gear 117, carried by the hollow sleeve 111, and meshes with a gear 130, carried by a vertical shaft 131, running in suitable boxes secured to the inner face of the end plate 50 and carrying at its lower end a worm 132, actuating a worm-wheel 133, mounted upon the inner end of a short horizontal shaft 134, journaled in and extending through the plate 50. A pinion 135 is secured to the outer end of this shaft and engages gear-teeth formed on the inner surface of the pattern-ring 128. A crescent-plate 136, recessed to receive the pinion 135 and having a smooth rim, forms a bearing for the apexes of the gear-teeth of the pattern-ring 128. This crescent-plate is secured by a bolt 138 to a bar 137, mounted on the end plate 50 and having a T-slot for receiving the head of the bolt 138. The crescent-plate is provided with a shoulder 139, between which and a large washer 140 on the bolt 138 the pattern-ring 128 runs.

For knitting garments of different sizes it 125 is necessary to provide pattern-rings, as 128, of greater or less circumference, and this construction permits the interchanging of rings

of various dimensions. For each patterning there is provided a crescent-plate 136 of the proper size, which may be secured to the bar 137 at any such point as will be found necessary for the proper engagement of the teeth of the pinion 135 and the internal gear of the pattern-ring.

As so far described the machine presents no new features, the automatic means for shifting the retracting-cams of the cam-carriages for changing the tension of the knitting and the means for rotating the pattern-cylinder 83 being shown and described in Letters Patent No. 670,159, granted to William K. Millholland and Ulysses G. Lee.

As previously described, a lock-stitch is formed by reciprocating one of the needle-plates longitudinally a distance equal to the spacing of the needles, so that each of its needles is advanced alternately on opposite sides of the coöperating needle of the other bank. To this end one of the plates, as 63, is mounted in longitudinal ways 141, Fig. 8, formed in the upper side rail 56 of the frame 25 of the machine.

A shaft 142 is journaled within the shaft-section 102, which is made tubular for its accommodation, and projects loosely through the pattern-cylinder 83 and enters the shaft-section 103. It is so joined to the shaft-section by a key 142^a as to permit independent longitudinal reciprocation of the latter, but insure its rotating with the shaft. There is mounted upon the extreme end of the last-named shaft-section a drum 145, carrying two annular series and relatively staggered sets of radially-projecting studs 146. A cam-block 147, secured, by means of suitable bolts, as 148, to a bracket-arm 150, attached 40 to the frame of the machine, coöperates with the studs 146. This cam is substantially diamond-shaped, having at both ends oppositely-inclined faces 151 152, and the cam is so positioned as to engage the inner faces of both series of studs. These two sets of studs are spaced apart so that members of each series are constantly in contact with the opposite faces of the cam, whereby the shaft 103 is caused to reciprocate longitudinally as it 50 rotates.

The width of the cam 147 determines, of course, the extent of this reciprocation and is shown as being sufficient to move the shaft a distance equal to the spacing of the needles. The shaft is provided with shoulders 143 144, engaging, respectively, the opposite ends of the bracket 104 within which the shaft is journaled, whereby the reciprocation of the shaft causes the desired reciprocation of the needle-bed 63, to which the bracket 104 is attached.

For convenience in assembling the parts the shaft 103 is comprised of two sections united by a coupling member 103^a, having

oppositely-directed threaded shanks which 65 screw into the two parts of the shaft, the body of this coupling member constituting the shoulder 143.

It being essential that the pattern-cylinder 83 shall rotate independently of the shaft-section 103 but reciprocate longitudinally therewith, in order that its relation to the needles be not disturbed in making the lock-stitch, the trunk of the pattern-cylinder is shown as being provided with a radially-projecting flange 83^a, which is seated within a chambered head 103^b at the inner end of the shaft 103, and an annular cap 83^b, screwed upon the head 103^b, overhangs the flange 83^a.

The rotation of the shaft 142 is controlled 80 by the pattern-ring 128 by the following described means: A pawl-arm 153, having a spring-pawl 154, swings upon the outer end of the shaft 142 and coöperates with a ratchet-wheel 149, secured to the shaft. A 85 portion of the ratchet-wheel is cut away, as indicated at 155, Fig. 3, to receive the end of the hollow shaft 102. An annular groove 156, Fig. 3, is cut in the shaft 102 adjacent its end and loosely receives the point of a 90 screw 157, set in the ratchet-wheel 149, so as to maintain a uniform relation of the parts when the pattern-cylinder 83 is reciprocated upon the shaft 142.

The free end of the pawl-arm rides upon 95 the periphery of a cam-plate 158, Figs. 3 and 17, which is loosely mounted on the constantly-driven sleeve 111, but may be made to rotate with it in the following manner: A disk 159 is fixed to the sleeve 111 adjacent to the cam-plate, and is provided with a plurality of recesses 161, Figs. 10, 15, intended to receive a pin 160, reaching through the cam-plate 158 and forced inwardly by means of a spring 162, extending over the end of the 100 shaft and secured to a plate 163, also loosely mounted on the shaft and having a segmental recess through which the pin projects. This plate 163 carries a wedge 164, Fig. 11, the point of which may pass under the overturned head of the pin 160, and also radially-projecting studs 165, which are intermittently engaged by a stop-arm 166 to prevent the rotation of the plate. This stop-arm is pivoted to the frame of the machine at 167, 110 and its forward end rides on the periphery of the pattern-ring 128 and is held thereto by a spring 166^a.

Normally the free end of the arm projects into the path of the lugs 165; but the pattern-ring is provided with elevated portions 168 169, Figs. 2, 12, which swing it out of their path. When rotation of the plate 163 is prevented by contact of the stop-arm with the pins 165, the forward movement of the 125 cam-plate 158 carries the head of the pin 160 up the inclined face of the wedge 164, so as to withdraw its inner end from one of the re-

cesses 161 in the disk 159. When the pin 160 is thus withdrawn, the disk 159 no longer drives the cam-plate 158, and it remains stationary, so that the shifting of the needle-plate 63 or racking movement is discontinued until the stop-arm 166 is again swung out of the path of the pins 165. The spring 162, forcing the head of the pin 160 against the inclined face of the wedge 164, will then 5 advance the plate 163 by a cam action between the head of the pin and the face of the wedge-block and insert the point of the pin 160 into one of the recesses of the disk 159, and so cause the cam-plate 158 to rotate 10 with the sleeve 111.

By giving the periphery of the patterning 128 the necessary conformation the racking may be produced at any desired point in the formation of the fabric and continued during as many rows of knitting as 15 may be required. In the machine as illustrated elevated portions 168 and 169 are formed on the pattern-ring to swing the stop-arm 166, so as to produce the racking 20 during several successive strokes of the machine just previous to the raising of the swinging lever 124 and just after allowing it to fall.

The rotation of the cam-plate 158, which 25 swings the pawl-arm 153 to produce the racking of the needle-plate when in operation, bears a definite relation to that of the driving-shaft 72, as the two are then positively connected by a system of bearing, including the spur-wheel 117, mounted on 30 the sleeve 111, the idler 116, the pinion 115, and the skew-gears 114. These gears are so proportioned that the shifting of the needle-plate always occurs at the end of a stroke of 35 the cam-carriage over the plate. Furthermore, to insure an instantaneous shifting of the needle-plate while the cam-carriage is at the end of its stroke the forward cam-faces of the cam-plate 158 have a sharp incline or 40 pitch, whereby the outward or effective stroke of the pawl-arm 153 is exceedingly rapid.

As before mentioned, provision is made for 45 knitting a half-cardigan stitch during the formation of a part of each article and for changing to another form of stitch from that used in the major part of the garment. When knitting the half-cardigan stitch, the needles of one bank, preferably the front bank, are 50 only partially advanced by the cams of the cam-carriage as it moves in one direction, but are completely advanced by the same cams moving in the opposite direction. To this end the advancing cam-plate 85 of one 55 of the cam-carriages, as 58, is movably attached to the floor of the carriage, having pins 170 projecting through slots 171 in the floor-plate, and a third pin 172 extending up through a slotted aperture in the body of the 60 carriage to a point in line with the worm- 65

wheels 96. This cam-plate is maintained in its advanced position by means of a small coil-spring 173; but the incline of the slots 171 being normal to the cam-face 86 the needle-lugs 80, bearing against this face as 70 the carriage moves forward, depress the cam-plate to a position indicated by dotted lines in Fig. 6 and ride over its upper edge 85^a without being completely advanced. As soon, however, as all of the needle-lugs have 75 passed over the cam-plate it is advanced by the action of the spring 173, and as the slots 171 are parallel to the cam-face 87 the cam-plate is not depressed during the return stroke. By this arrangement of the advancing-cam the needles of one side of the machine are advanced only far enough during the forward stroke to receive a new strand of 80 yarn without passing the loops already held in their hooks over the latches. No stitches 85 are therefore cast off when the needles are depressed by the retracting-cam 88; but two strands of yarn are held in the hooks to be cast off as a double stitch during the return stroke of the carriage. 90

When the retracting-cams 88 and 89 are shifted to the forward position (indicated by dotted lines in Fig. 6) for increasing the tension of the stitches incident to the formation of the more closely knitted parts of the garment, a contacting piece 174, Fig. 9, carried by an arm 175, projecting from one of the worm-wheels 96, is brought into the path of the pin 172 to prevent the depression of the advancing-cam plate 85 by the pressure 95 of the needle-lugs against its forward face. With the cams in this position the needles of both sides of the machine receive a single strand of yarn each time they are advanced and cast off a single stitch each time they are 100 retracted. This relative arrangement of the mechanism for shifting the retracting-cams and that for locking the advancing-cam is of course not essential to the operation of either. 105

The stop 174 is adjustably secured to the 110 arm 175 by means of set-screws 176, passing through slots 177 in the arm, so that it may be set to come in contact with the pin 172 when the worm-wheel 96 is in the position corresponding to the setting of the retracting-cams for the desired tension of knitting. 115

The operation of the machine as illustrated is as follows: While the cam-engaging finger 126 of the swinging lever 124 rides upon either of the cam-blocks 127, the retracting-cams 88 89 are shifted to the dotted-line position of Fig. 6, and the stop 174 is thrown 120 into the path of the pin 172 to prevent the retraction of the cam 86. A fabric is now formed composed of closely-knitted stitches, 125 and which may be the cuff portion of a garment. The stitch may be of any form, in which all the needles in action cast off a single loop of yarn at each stroke of the cam-carriage, the particular variety of stitch be- 130

- ing knitted depending on the configuration of the pattern-cylinders 83. Since the operation of the parts of the machine to which the present invention relates is entirely independent of the proportion of needles knitting at any time in the formation of the fabric, the details of these cylinders have not been shown. When the cam-block 127 passes out from under the finger 126, the spring 125 swings the lever 124, so as to shift the gear-rack 119. This by rotating the shafts 99 and 100 changes the setting of the parts of the cam-carriages to that shown in full lines in the various figures of the drawings and removes the stop 174 from the path of the pin 172. The cams now operate upon the needles and are acted on by them in such a way as to produce the half-cardigan stitch previously described and a more open fabric.
- During the formation of this part of the garment, and preferably immediately after the change is made to this form of stitch, the stop-arm 166 is engaged by one of the elevations 168 of the pattern-ring 128 and swung out of the path of the pins 165. This causes the racking movement to begin, and it continues during the formation of several rows of knitting or until the elevated portion 168 passes out from under the point of the stop-arm 166, and this arm is again swung into the path of the pins 165 by the action of the spring 166^a. The lock-stitch produced by this racking movement forms a more closely knitted fabric than the half-cardigan stitch produced without the racking and is a suitable gradation between this and the taut stitches of the cuff portion of the garment. After the elevation 168 passes out of engagement with the stop-arm 166 and until this is reached by one of the elevations 169 of the pattern-ring a loosely-knitted fabric composed of half-cardigan stitches is produced. Several other rows of interlocked stitches are formed when the stop-arm 166 is swung out of the path of the pins 165 by the elevated portion 169 of the pattern-ring, and in the machine organized, as shown, immediately after this elevated portion passes beyond the point of the stop-arm the lever 124 is swung by the cam-block 127 to change the setting of the parts of the cam-carriages for again forming the more closely knitted stitch.
- It will be understood from the foregoing that the fabric produced by the machine comprises a plurality of closely-knitted portions and intervening portions of more open knitting joined to the closely-knitted portions at either end by connecting-webs of interlocked stitches. The fabric may be divided as desired by cutting through any of such webs, which preferably are not less than three courses of stitches in length, whereby if the cut is made through an intermediate one of such courses a selvage edge at one side and a series of lock-stitches at the other side of the
- cut results. It has been found convenient to separate the fabric by cutting through all of those connecting-webs of interlocked stitches which follow the open knitting. In this way the fabric is divided into a plurality of garments, such as sweater-sleeves, each having a closely-knitted elastic cuff and a loosely-knitted open body, the first several rows of stitches of the body being so interlocked as to be intermediate in mesh between those of the cuff and of the remainder of the body and forming a fine appearing connection between the two. Each garment has, moreover, a non-raveling edge at both top and bottom.
- The recurrence of the several forms of stitches is of course determined by the conformation of the pattern-wheel, which may be changed as desired.
- Rotative connection is established between the shaft-section 102 and the pattern-cylinder 83 by pins 102^a, projecting from a flange 102^b on the end of the shaft-section into suitable sockets in the end of the trunk of the pattern-cylinder. When the cylinder 83 is longitudinally reciprocated, there is a movement of the cylinder-trunk on the pins; but the reciprocation of the cylinder is not sufficient to cause these parts to be separated.
- In the preferred construction of the machine the cam-plate 158 takes the form of a star having three points and is so driven as to swing the pawl-arm 153 and shift the needle-plate 63 between each complete cycle (advance and return stroke) of the cam-carriages. The pattern of the knitting may be changed by substituting for this cam one of different form which will shift the needle-plate more or less frequently. In Fig. 21 is shown such a cam 178, having six points and which may be employed to shift the needle-plate at the end of each stroke of the carriages. When the needle-plate is so shifted, a fabric of interlocked stitches is produced, the form of the stitches having a peculiar ornamental effect.
- I claim as my invention—
1. In a knitting-machine, in combination, a needle-bed; a cam-carriage coöperating therewith; a yielding spring-returned needle-advancing cam and a movable needle-retracting cam carried by the carriage; a crank-shaft having a wrist-pin in engagement with the retracting-cam, and a stop-arm for engaging an appurtenance of the advancing-cam; and means for oscillating the crank-shaft.
  2. In a knitting-machine, in combination, a needle-bed; a cam-carriage coöperating therewith; a yielding spring-returned needle-advancing cam, and a movable needle-retracting cam carried by the carriage; a crank-shaft having a wrist-pin in engagement with the retracting-cam; an arm car-

ried by the crank-shaft; a stop for engaging an appurtenance of the advancing-cam adjustably secured to the arm; and means for oscillating the crank-shaft.

5. 3. In a knitting-machine, in combination, a needle-bed; a cam-carriage coöperating therewith; a yielding spring-returned needle-advertising cam, and a movable needle-retracting cam carried by the carriage; a crank-shaft having a wrist-pin in engagement with the retracting-cam; an arm carried by the crank-shaft; a stop for engaging an appurtenance of the advancing-cam adjustably secured to the arm; a worm-wheel 15 mounted on the crank-shaft; a shaft supported over the needle-bed; a worm sliding on and turning with such shaft and carried by the cam-carriage; a pinion on the shaft; a rack engaging the pinion; a swinging lever 20 for reciprocating the rack having a cam-engaging toe; a pattern-wheel having a cam-surface for swinging the lever; and means for rotating the pattern-wheel.

4. In a knitting-machine, in combination, 25 a needle-bed; a shiftable needle-plate mounted on the bed; a shaft journaled in the needle-plate and longitudinally movable therewith; a cam-wheel mounted on the shaft; a fixed cam-block coöperating with the cam-wheel; and means for rotating the shaft.

5. In a knitting-machine, in combination, a needle-bed; a shiftable needle-plate mounted on the bed; a shaft journaled in the needle-plate and longitudinally movable therewith; a drum mounted on the shaft; cam-engaging pins secured to the drum; a cam-block adjustably fixed and coöperating with the pins; and means for rotating the shaft.

6. In a knitting-machine, in combination, 40 a needle-bed; a shiftable needle-plate mounted on the bed; a shaft journaled in the needle-plate and longitudinally movable therewith; a drum mounted on the shaft; cam-engaging pins secured to the drum; a cam-block adjustably fixed in position; a ratchet-wheel 45 fixed to the shaft; a pawl-arm rotatable on the shaft; a spring-pawl carried by the arm and engaging the ratchet-wheel; a cam for swinging the pawl-arm; and means for rotating the cam.

7. In a knitting-machine, in combination, 55 a needle-bed; a shiftable needle-plate mounted on the bed; a shaft journaled in the needle-plate and longitudinally movable therewith; a drum mounted on the shaft; cam-engaging pins secured to the drum; a cam-block adjustably fixed in position; a ratchet-wheel 60 fixed to the shaft; a pawl-arm rotatable on the shaft; a spring-pawl carried by the arm and engaging the ratchet-wheel; a shaft journaled in the frame of the machine and driven from its rotating parts; a cam loosely mounted on the shaft for swinging the pawl-arm; and a disk secured to the shaft adjacent the cam; a spring for seating the pin; a wedge-plate for withdrawing the pin; a stop-arm for engaging the wedge-plate; a cam-ring for 65 oscillating the stop-arm; and means for rotating the cam-ring.

8. In a knitting-machine, in combination, a needle-bed; a shiftable needle-plate mounted on the bed; a shaft journaled in the needle-plate and longitudinally movable therewith; a drum mounted on the shaft; cam-engaging pins secured to the drum; a cam-block adjustably fixed in position; a ratchet-wheel 70 fixed to the shaft; a pawl-arm rotatable on the shaft; a spring-pawl carried by the arm and engaging the ratchet-wheel; a shaft journaled in the frame of the machine and driven from its rotating parts; a cam loosely mounted on the shaft for swinging the pawl-arm; a disk secured to the shaft adjacent the cam; a pin mounted in the cam for engaging the disk; a spring for seating the pin; a wedge-plate for withdrawing the pin; a stop-arm for 75 engaging the wedge-plate; a cam-ring for swinging the stop-arm; and means for rotating the cam-ring.

9. In a knitting-machine, in combination, a needle-bed; a shiftable needle-plate mounted on the bed; a cam-carriage coöperating therewith; a hanger secured to the plate; a longitudinally-extensible shaft comprising a pair of coaxial members connected to revolve together, one thereof being journaled in the hanger and the other in the frame of the machine, shoulders on the first-named shaft member for engaging the hanger, means for longitudinally shifting said shaft member, an independently-revolvable pattern-cylinder 90 mounted on the shaft and connected to shift with the shiftable shaft member, a sleeve enclosing the second-named shaft member and operatively connected with the pattern-cylinder to impart rotation thereto; and means 100 for turning the sleeve.

10. In a knitting-machine, in combination, a reciprocating needle-plate; a reciprocating pattern-cylinder; and means for causing the simultaneous and uniform movement of said members.

11. In a knitting-machine, in combination, a needle-plate; a pattern-cylinder; means for causing the simultaneous and uniform reciprocation of such members; and means for rotating the cylinder independent of its reciprocation.

12. In a knitting-machine, in combination, a pattern-cylinder; a pair of coaxial shafts carrying the cylinder; means for independently rotating such shafts; and means actuated by one of the shafts for causing its reciprocation.

13. In a knitting-machine, in combination, a reciprocating needle-plate; a constantly-driven member; means for reciprocating the needle-plate and being normally engaged with the driven member; a pattern-ring; and

means actuated by the pattern-ring for disconnecting the plate-reciprocating mechanism from the driven member.

14. In a knitting-machine, in combination, a needle-bed; a cam-carriage coöperating therewith; a yielding spring-returned needle-advancing cam and a needle-retracting cam carried by the carriage; a shaft mounted on the carriage and having a stop-arm movable into the path of an appurtenance of the advancing-cam; a worm-wheel mounted on the shaft; a shaft supported over the needle-bed; a worm sliding on and turning with the last-named shaft and carried by the cam-carriage;
15. a pinion on the last-named shaft; a rack engaging the pinion; a swinging lever for reciprocating the rack having a cam-engaging

toe; a pattern-wheel having a cam-surface for swinging the lever; and means for rotating the pattern-wheel.

15. In a knitting-machine, in combination, a needle-bed; a reciprocatory needle-plate mounted on the bed; a cam-carriage coöperating therewith; a longitudinally-extensible shaft comprising a pair of coaxial members connected to revolve together, one thereof being journaled in the needle-plate and the other in the bed; an actuating-cam carried by the first-named shaft member; and means carried by the bed for revolving the shaft.
